CUTTING MECHANISM FOR ROTARY PRINTING MACHINES

Michael Mahon, Brooklyn, N. Y., assignor to Irving Trust Company, temporary trustee for R. Hoe & Co., Inc., New York, N. Y., a corporation of New York

Application November 25, 1933, Serial No. 699,739

12 Claims. (Cl. 164—67)

This invention in general relates to cutting and folding mechanism for newspaper printing machines, and has for its object the provision of an improved means for severing the associated webs which are cut and folded to form the finished product.

A further object of the invention is to provide in a rotary cutting mechanism, a cylinder having novel knife actuating means mounted thereon and operated by engagement with a coacting cylinder.

It is also an object of the invention to provide a rotary web cutting mechanism of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed.

The preferred embodiment of the invention is illustrated in the accompanying drawings, wherein:

Figure 1 is a fragmentary elevational view of a pair of coacting cutting and collecting cylinders in one of which an embodiment of the invention has been incorporated, and illustrating the position of the cutting mechanism when the knife is projected from the cylinder wherein same is mounted; certain parts being broken away and others shown in section;

Figure 2 is a fragmentary sectional view taken on the line and as viewed in the direction of the arrow 2 of Figure 1;

Figure 3 is a fragmentary diagrammatic view showing the position of the parts prior to the projection of the knife;

Figure 4 is a view of the periphery of the cutting cylinder as viewed in the direction of arrow 4 of Figure 3; and

Figure 5 is a sectional view taken on the line and as seen in the direction of the arrow 5 of Figure 2.

In the drawings wherein similar characters of reference indicate corresponding parts in the several views of the preferred form of the invention, 6 designates a folding cylinder and 7 a coacting cutting cylinder. The folding cylinder 6 is provided with the usual sheet taking means indicated generally at 8, similar means 8' being arranged in the cutting cylinder in accordance with the usual practice. A cutting abutment 9 is suitably supported in the folding cylinder and

receives the knife or blade 10 of the cutting cylinder 7, the said knife being actuated by mechanism forming the feature of the present invention.

The knife 10 is arranged between and projects outwardly of a pair of plates or blocks 11 longitudinally positioned in a carrier or holder 12 which may be substantially of U-shaped configuration or channel iron construction, the said knife and cheek blocks being held to the carrier 12 by screws 13. The carrier 12 is in turn secured by screws 14 to a bar 15, having cam edges 16, best seen in Figure 2. The holder and the bar 15 are slidably mounted in a pocket or recess 17 formed in the body portion of the cutting cylinder 7. Each cam portion 16 of the bar 15 is in turn engaged by an arm or lug 18, formed on an adjacent member 19, pivoted on a shaft or stud 21 carried by arms 29 formed on a face block 30. The said face block 30 and members 20 carried thereby are set in the end faces of the aforesaid cylinder 7 and secured thereto by the bolts 32 and screws 32'. Each member 19 is also provided with a second arm or lug 22 oppositely disposed to the arm 18 and adapted to be engaged by an inner end of a plunger 23 arranged in a pocket or recess 24 formed in the face block 30. The plunger 23, as best shown in Figure 2, is formed with an annular flange 25 engaged by one end of a spring 26 encircling the body portion of the plunger 23, the other end of the spring 26 being seated against an inner wall of the pocket 24 through which a portion of the plunger 23 protrudes. By further inspection of Figure 2, it will be seen that each plunger 23 is formed with a stem or tongue 27 slidably received in a bushing 28 threadedly engaged in the pocket 24, the said stem or tongue 27 normally being adapted to project exteriorly of the bushing 28. The bushing 28 serves to permit the insertion of the plunger 23 into the adjacent pocket 24 and also to slidably retain same therein while permitting the tongue 27 to normally protrude exteriorly of the cutting cylinder to the extent indicated in Figure 3.

The knife 10 is normally maintained in retracted position by springs 31, each of which encircles a projection or stem formed as a part of the head of each screw 14. One end of the spring 31 is engaged against a projecting portion 34 of the aforesaid block 30, the other end of the said spring being engaged against a projecting portion 35 formed on the holder 12. It is to be understood that the construction described above is provided by duplicating the parts 36

shown in Figure 2 at the opposite end of the cutting cylinder 7.

In order to permit cutting of products of different thicknesses, it is necessary to provide for adjusting the space between the cutting cylinders. Adjusting mechanism for the cylinder bearings is not herein shown, but is well-known in the art. Provision for adjusting the cutting mechanism relative to the cylinder is made and, 10 comprises a plurality of abutment screws 36 each of which engages an adjacent stem 27 to actuate the knife. Each abutment screw 36 is adjustable in a tapped hole 37 in the cutting cylinder 7 and may be locked by means of a jam element 15 or plug 38 thrust into engagement therewith by a set screw 39. It will be observed that when the cylinders are separated to cut a heavier product, the abutment screws may be backed out and locked in proper position so that the 20 knife will enter the cutting rubber the requisite distance to sever the products.

It will also be understood that in cases where the products to be cut are of an invariable thickness not requiring a spacing or disposition 25 of the cylinders other than the normal one illustrated, the abutment screw 36 may be dispensed with and the surface of the cylinder 6 made uniform or level with adjacent portions 30 of its periphery in the conventional manner, the outer extremity of the plunger stem 27 then being adapted to directly contact the surface of the cylinder 6 as the two cylinders 6 and 7 rotate.

The function and general manner of operation 35 of the device may now be summarized as follows:

Assuming the folding and cutting cylinders 6, 7 respectively, are rotating in the direction indicated by the arrows of Figure 1, it will be 40 observed that as the stems or projections 27 of the plungers 23 are engaged by the heads of the screws or abutments 36 of the folding cylinder 6, further angular movement of the said cutting and folding cylinders will thrust the 45 plunger 23 inwardly, thereby engaging the innermost end of same with an adjacent edge of the arm 22, consequently, angling or turning the member 22 about its pivot 21 and engaging the oppositely disposed arm 18 thereof with the 50 cam edge 16 of the bar 15. Further movement of the plunger 23, as the cylinders 6 and 7 rotate, will cause the knife 10 to engage and sever the web W, which has been previously 55 engaged by the respective pins 8 or 8' according as to whether the product is a non-collected or collected one, it being understood that when the pins 8 are acting for a non-collected product, the pins 8' will be withdrawn; and in the event of a collected product, the pins 8' will 60 act to take the product which is later transferred to the folding cylinder in accordance with well known practice. As the folding and cutting cylinders continue to rotate, the plunger 23 will be projected out of the pocket 24 to the extent indicated in Figure 3, in which latter position, it is again ready for engagement with the abutment screw 36 or the periphery of the collecting cylinder 6 in the manner described above while the knife 10 is retracted into the cutting 65 cylinder 7.

It will be noted that by means of the present invention, the web severing knife is normally held within the cutting cylinder, but is quickly and forcibly projected at the proper time to most effectively make the cut.

It will be understood that the invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

What I claim is:

1. In a device of the character described, the combination with coacting cylinders of a rotary printing machine; of a web severing knife arranged within one of said cylinders, and means mounted on the cylinder having the knife and actuated by contact with means on another of the cylinders for operating said knife.

2. In a rotary cutting mechanism for a printing machine, a first cutting cylinder and a second cutting cylinder coacting therewith, a cutting knife reciprocatingly mounted in a first cylinder and movable radially to the axis of said cylinder, and actuating means normally projecting from said first cylinder and adapted to operate said knife when said actuating means is operated by engagement with means arranged on a second cutting cylinder.

3. An arrangement as specified in claim 1 wherein the first mentioned means includes a member normally protruding from the cylinder whereon the said first mentioned means are mounted.

4. An arrangement as specified in claim 1 wherein the first mentioned means includes a plunger normally protruding from the cylinder whereon the said first mentioned means are mounted, a spring engaged with the plunger and resilient means for normally maintaining the knife within the last mentioned cylinder.

5. In a device of the character described, the combination with coacting folding and cutting cylinders of a rotary printing machine; of a knife reciprocatingly mounted in said cutting cylinder, plunger means arranged in the cutting cylinder, a member pivotally mounted within the cylinder and adapted to be engaged by the plunger means, means arranged between the member and the knife whereby when said plunger means is engaged by means secured to the folding cylinder as both of said cylinders rotate, the member will be moved and said knife will be thrust out of said cylinder, and resilient means for normally maintaining the plunger means in position to be engaged by the means secured to the collecting cylinder.

6. In a rotary cutting and folding mechanism, the combination of coacting cylinders, one of said cylinders having a knife slidably mounted in the interior thereof, a cheek block for said knife, a bar engaged with said cheek block, a member pivotally mounted within the cylinder having the knife and engaged against said bar, and a spring pressed plunger normally projecting from the last mentioned cylinder and adapted to be engaged by the periphery of the other of said cylinders, said plunger having an inner end engaging said member.

7. In a device of the character described having folding and cutting cylinders, a knife slidably mounted in the cutting cylinder, means secured to said knife and coactingly engaged with a member pivotally mounted in the cutting cylinder, resilient means normally maintaining said knife in contact with the member, and plunger means normally protruding out of the cutting

- cylinder having an inner end engaged with said member, whereby when said cutting and folding cylinders are rotated the plunger means will be engaged by the periphery of the folding cylinder 5 and thrust inwardly thereby protruding said knife out of the cutting cylinder, and resilient means for returning the plunger means to the normal projected position.
8. In a device of the character described, the 10 combination with cutting and folding cylinders adapted to accommodate a web therebetween; of a web engaging knife, a bar fastened to said knife and engaged with a member rockingly mounted in the cutting cylinder, spring means 15 normally maintaining the bar in engagement with the member, plunger means also engaged with the member, and resilient means for normally maintaining one end of said plunger exteriorly of the cutting cylinder, whereby when 20 the plunger is actuated by contact of the folding cylinder, the member will be rocked and the bar will engage the knife and thereby project same against the web interposed between the cutting and folding cylinders.
9. In a device of the character described, the 25 combination with a pair of cutting and folding cylinders, of a knife movably mounted in said cutting cylinder, and means normally protruding exteriorly of said cutting cylinder for actuating said knife independently of driving mechanism 30 and parts connected to the driving mechanism

for said cutting and folding cylinder, whereby the knife may be actuated to sever a web and then automatically returned to position within the cutting cylinder.

10. In a device of the character described, the 5 combination with coacting cylinders of a rotary printing machine; of a web severing knife arranged in one of the cylinders, an abutment on another of the cylinders, and means mounted on said first mentioned cylinder and actuated by contact with said abutment for operating said knife to sever a web.

11. The combination with coacting cylinders 10 of a rotary printing machine; of a web severing knife arranged in one of the cylinders, an abutment on another of the cylinders, 15 means for adjusting the abutment to various positions relatively to the periphery of the cylinder whereon same is mounted, and other means mounted on the first mentioned cylinder and actuated by 20 contact with said abutment for operating said knife to sever a web.

12. The combination in a rotary printing machine, 25 of a pair of cylinders, a web severing knife arranged within one of the cylinders, and means mounted on the cylinder having the knife and actuated by a surface rotating with the other cylinder for operating said knife to sever a web.

MICHAEL MAHON. 30
